CLAIM

The ornamental design for a jewelry ornament, as shown and described.

DESCRIPTION

FIG. 1 is a front elevation view of a jewelry ornament showing my new design in a position of use with an exemplary pendant chain;

FIG. 2 is a front perspective view thereof, shown with the exemplary pendant chain removed; and,

FIG. 3 is a rear view thereof.

The pendant chain of FIG. 1 is shown for environmental purposes and forms no part of the claimed design.

The evenly spaced broken lines are shown for the purpose of illustrating environmental subject matter of an exemplary pendant chain forming no part of the claimed design.

The dot-dash broken lines are shown for the purpose of illustrating the boundaries of the claim and form no part thereof.

The shaded portions of the circular apertures shown in FIG. 3 show the depth of the apertures as through-holes in the jewelry ornament, to allow for the settings of the respective stones shown in FIGS. 1 and 2 on the front of the jewelry ornament, and to let light therethrough, as would be known to those skilled in the art of jewelry making. The through-holes form no part of the claimed design and are shown for environmental purposes only.
